UNITED STATES PATENT OFFICE

ROBERT E. WILLARD, OF MINNEAPOLIS, MINNESOTA, ASSIGNOR, BY MESNE ASSIGNMENTS, TO BRIQUET ENGINEERING COMPANY, OF MINNEAPOLIS, MINNESOTA, A CORPORATION OF DELAWARE

PROCESS FOR MAKING BRIQUETTES

Application filed April 28, 1930. Serial No. 447,926.

My invention provides an improved process for the making of briquettes and, generally stated, consists of the novel manipulations and successive steps of manipulations hereinafter described and defined in the claim.

The nature of the process will be made clear in the description of the use of the improved apparatus for carrying out the said process and a preferred form of which apparatus is illustrated in the accompanying drawings, wherein like characters indicate like parts throughout the several views.

Referring to the drawings:

15 Fig. 1 is a diagrammatic view illustrating a complete briquetting plant or system;

Fig. 2 is a view partly in elevation and partly in vertical section illustrating that portion of the plant that involves the improved process;

Fig. 3 is a horizontal section taken on the line 3—3 of Fig. 2;

Fig. 4 is a transverse vertical section taken on the line 4—4 of Fig. 3;

25 Fig. 5 is an end elevation of the preheating mixer shown in horizontal section in Fig. 3, and in transverse section in Fig. 4;

Fig. 6 is a transverse section taken through the conditioning mixer on the line 6—6 of Fig. 2 and showing also a fan with connections for exhausting gases from said mixer; and

35 Fig. 7 is an enlarged vertical section taken on the line 7—7 of Fig. 2 through the binder sprayer.

Referring first to the diagram view Fig. 1 and briefly noting the order of the several operations in the making of briquettes by the apparatus illustrated but without discussing in detail any of said actions, the complete system illustrated comprises as follows: The raw coal is introduced into a raw coal bin 8, from thence it is delivered through a drier 9, from thence is elevated to a dry coal bin 10, from thence is delivered to a crusher 11, thence by elevator 12 is delivered to ground coal bin 13, from thence is delivered through a preheating mixer 14, from thence through a binder sprayer 15, from thence through a fluxer 16, from thence through a conditioning

mixer 17, from thence to briquette press 18 and from thence onto a cooling table 19.

The above noted elements 8 to 13, inclusive, and 18 and 19 are standard well known construction such as hitherto employed in briquette plants and the novelty of the apparatus here claimed is found in the elements located between the said above noted elements 13 and 18 and these parts will now be described more in detail.

The coal delivered into the ground coal bin 13 will be suitably ground for the forming of briquettes, will be dry and quite hot, say at a temperature of about 175 degrees F. From the bin 13, this ground briquette material will be fed into one end of the preheating mixer 14 under the action of a power-driven measuring device such as used for feeding of grain and comprising a rotary paddle-equipped head 20, the shaft of which projects 70 and is provided with a gear 21. The preheating mixer 14 is an approximately horizontal tubular steam-jacketed shell, the steam chamber 22 of which receives live steam through supply pipe 23, shown in Fig. 2. 75 Steam jets 24 that receive super-heated steam from supply pipe 25 open at several different points into the interior of the preheating mixer 14, as also best shown in Fig. 2.

Extended longitudinally through said preheater casing 14 is a pair of parallel shafts 26 that are journaled in the ends of said shell and are connected for rotation in the same direction through spur pinions 27 on said shafts and an intermediate pinion 28 80 journaled on the shell. One of the shafts 26 is provided with an additional gear 29 through which and motor-driven gears, not shown, motion may be imparted to the shafts. The said shafts are provided with radially 85 projecting spirally arranged mixer blades 30 that are obliquely set in the same direction so that while mixing the material, they propel the same longitudinally of the shell and discharge the same through a spout 31 at the 90 discharge end of said shell.

It is here important to note that the shell of the preheating mixer 14 is air-tight so that when the interior thereof is charged 100 with super-heated steam, the coal will be

thoroughly agitated in an inert atmosphere and may be and preferably will be brought to a temperature of approximately 400 degrees F. The temperature, however, to which the coal should be raised in this preheating mixer will depend somewhat on the nature of the coal or briquette material, but due to the fact that it is agitated in an inert atmosphere, that is free from free oxygen, the temperature of the coal may be raised to a much higher temperature but at any rate, to a temperature close to the temperature where volatilization begins and at a temperature at which oxidation of the coal would take place in the presence of atmosphere containing oxygen, and this, in the apparatus described, can be done without danger of oxidation or combustion of the coal. At this high temperature the coal will more intimately unite with a binder, but the mixing of the binder therewith should also take place in an inert atmosphere or in an atmosphere in which oxygen is not present. Hence the hot coal from the preheating mixer is next delivered to and through the binder mixer 15.

This binder mixer is of a novel construction fully disclosed and claimed in a companion application, Serial No. 447,925, filed 30 of even date herewith and is illustrated more in detail in Fig. 7. However, for the purposes of this case the said binder sprayer may be quite briefly described and further details will be found by reference to the said 35 companion application.

Within the shell of the binder sprayer is a plurality of annular conical deflectors 32 and extended axially through said sprayer is a hollow shaft 33 plugged at 34 and provided with impeller heads 35. The binder material will usually be asphalt or an asphalt compound fed downward through the upper portion of shaft 32 and from thence outward through discharge ducts or passages 40 45 36 formed in the upper head 35. The deflecting cones 32 are preferably hollow and supplied with live steam through a pipe 37 that is connected to the steam pipe 23. Steam jets 38 are connected to the super-heated steam pipe 25 and are positioned to discharge into the upper portion of the binder sprayer obliquely downward in the direction of rotation of the shaft 32 so that the briquette material delivered into the upper end of said sprayer will be given a whirling motion. The ground coal or briquette material dropping from the first deflector onto the upper rotating impeller head 35 will be thrown 50 55 outward against the oblique under surface of the upper deflector and will be thoroughly commingled with the spray of binder delivered from the ducts 36 of said upper head. The supply of binder is preferably delivered only from the upper head but the successive deflecting and mixing actions will be re-

peated as the material passes downward from the second deflector to the second impeller head and from the third deflector to the third or lowermost impeller head so that the coal and binder will be very thoroughly 70 mixed when it reaches the bottom of said sprayer and is delivered into the receiving end of the fluxer 16.

The fluxer 16 is substantially a repetition or duplication of the preheating mixer, that is, it has a steam jacket 39 and is provided with parallel shafts 40 that are driven in the same direction and are provided with spirally arranged oblique mixing blades 41 that impel the briquette material from the receiving toward the delivery end of said fluxer. The steam jacket 41 is supplied with steam from a branch of steam pipe 37. Steam jets 42 open to the interior of the fluxer 16 and these, as shown, receive super-heated steam from the branch 25^a of super-heat supply pipe 25. By the time the briquette material reaches the delivery end of the fluxer 16, its temperature will be reduced probably down to about 350 degrees F. and it will be delivered from the fluxer into the conditioning mixer through discharge conduit 43 at about that temperature.

A chemical action is started in the binder sprayer which is substantially as follows: 95 The highly heated coal, coming from the preheating mixer at a high temperature (400°) comes into contact with the binder at 175°. The action of the sulphur in solution in the asphalt is retarded in the binder mixing tanks as much as possible, by using only a temperature in the mixing tanks 15° in excess of the melting point of the asphalt, so that the resulting solution is only fluid 100 enough to handle through the binder pumps. 105

When the binder comes in contact with the coal, which is at a much higher temperature (400°) the temperature of the binder is immediately raised to the high temperature of the coal. This high temperature hastens the desired chemical reaction in both coal and binder, called polymerization, where the hydrogen in the bitumens in both coal and binder unite with sulphur in solution in the binder, forming hydrogen sulphide (H₂S) which passes off and is wasted.

This polymerization eliminates some of the hydrogen from the hydrocarbon molecules, thereby enriching the hydrocarbons in carbon, and the molecules become rearranged into molecules of higher molecular weight.

The above described action continues throughout the fluxer and hence the importance of keeping up and a continuing the mixing and agitation operation at a high temperature for a considerable period of time after the material leaves the sprayer. The so-called fluxer performs this function.

The function of the so-called conditioning

mixer 17 is to reduce the temperature of the briquette material to such temperature that it can be properly formed into briquettes and it is important that while this cooling operation takes place, that the agitation and mixing of the material is continued. The shell of this conditioning mixer is of substantially the same form as preheating mixer except that it is not steam jacketed. It has the same 5 parallel shafts 44 driven in the same directions and provided with oblique mixing blades 45 that mix the material and progressively force the same toward the delivery end of the mixer from whence it is delivered 10 through a discharge passage 46 to an ordinary briquette machine indicated as an entirety by the numeral 47. To cool the briquette material while it is passing through the conditioning mixer, water jets 48 are provided and these are connected to a water supply pipe 49. To draw off the gases and vapors formed within the conditioning mixer 15 17, it is shown, as provided with a discharge pipe 50 connected to a blower 51; and in practice the other mixing devices may be likewise connected to a discharge fan for carrying off the gases and vapors. 20

The jets 48, as indicated, may be connected either to a water supply or to a source of saturated steam and hence it will be understood 25 that broadly the one is the equivalent of the other, although the water will have the greater cooling effect. Saturated steam, however, is of much lower temperature than the 30 material introduced into the conditioning mixer and hence would also have, to a less extent, a cooling action. 35

The binding fluid may be contained in any suitable supply tank or receptacle, such as 40 an elevated tank 52 that delivers to a pump 53. This pump 53 may be of any suitable well known rotary measuring type such as a rotary gear pump that is connected to deliver the binder and material in measured quantity 45 to the upper end of the hollow rotary shaft 32. The shaft 54 of the rotor of this pump 53 is connected by gears 55 and 56 to a transverse shaft 57, and the other end of this shaft 57 is connected by a spur pinion 58 and the 50 hitherto noted gear 21 to the rotary paddle-equipped head 20 of the measuring coal-feeding device. From this it follows that the coal or briquette material and the binding material will be supplied to the apparatus in 55 definite proportionate quantities. This proportionate quantity may, of course, be varied by changing the gears 55 and 56 or the gears 21 and 58. As shown, shaft 57 is driven from a small electric motor 59 through a chain or 60 link belt 60 and co-operating sprockets. 65

What I claim is:

The process of making briquettes which includes heating the ground briquette material approximately to the temperature of its incipient distillation by the application of 65

steam directly in contact therewith, agitating the same and introducing thereinto a briquette binder while maintaining substantially the temperature above indicated and while in direct contact with steam, further 70 continuing the agitation of the briquette material and binder while subjecting the same to a spray of water to cool the same down to a proper temperature for forming briquettes, and then pressing said briquette material into 75 the form of briquettes. 80

In testimony whereof I affix my signature.
ROBERT E. WILLARD.
